UNITED STATES PATENT OFFICE

128,616

DESIGN FOR A BASIN HOLDING STAND

John W. Boren, Marinette, Wis.

Application May 2, 1941, Serial No. 100,744

Term of patent 7 years

To all whom it may concern:

Be it known that I, John Wm. Boren, a citizen of the United States and a resident of Marinette, county of Marinette, and State of Wisconsin, have invented a new, original, and ornamental Design for a Basin Holding Stand, of which the following is a specification, reference being had to the accompanying drawing, forming a part thereof, in which Fig. 1 is a perspective view of a basin holding stand showing my new design. Fig. 2 is a top plan view of the stand.

I claim:

The ornamental design for a basin holding stand, substantially as shown.

JOHN WM. BOREN.
